UNITED STATES PATENT OFFICE.

EDWARD A. REESE AND RICHARD L. ST. CLAIR, OF PARIS, ILLINOIS.

DESIGN FOR A WINDOW-SCREEN.

SPECIFICATION forming part of Design No. 34,863, dated July 30, 1901.

Application filed June 20, 1901. Serial No. 65,363. Term of patent 14 years.

To all whom it may concern:

Be it known that we, EDWARD A. REESE and RICHARD L. ST. CLAIR, citizens of the United States, residing at Paris, in the county of Edgar and State of Illinois, have invented and produced a certain new and original Design for Window-Screens; and we do declare the following to be a full, clear, and exact description of the invention, such as will enable others skilled in the art to which it appertains to make and use the same.

This invention relates to a design for a window-screen, and is shown in the accompanying drawings, in which—

5 Figure 1 is a perspective view of the window-screen. Fig. 2 is a vertical longitudinal section of the same, and Fig. 3 is a horizontal section.

The leading or material features of the de-

sign consist of an open rectangular frame 1, 20 provided at the top and bottom of the opening therein with outwardly-projecting brackets 2, connected by columns or posts 3, and a screen 4, closing the space between the outer face of the frame and the edges of said 25 brackets.

Having thus described our invention, what we claim is—

The design for a window-screen, substantially as herein shown and described. 30

In testimony whereof we have hereunto set our hands in presence of two subscribing witnesses.

EDWARD A. REESE.
RICHARD L. ST. CLAIR.
